UNITED STATES PATENT OFFICE.

JOHN J. MACMULKIN, OF LONG ISLAND CITY, NEW YORK, ASSIGNOR TO THE DAIMLER MANUFACTURING COMPANY, OF LONG ISLAND CITY, NEW YORK, A CORPORATION OF NEW YORK.

VAPORIZER FOR HYDROCARBON-ENGINES.

SPECIFICATION forming part of Letters Patent No. 759,624, dated May 10, 1904.

Application filed December 8, 1903. Serial No. 184,320. (No model.)

To all whom it may concern:

Be it known that I, JOHN J. MACMULKIN, a citizen of the United States of America, residing in Long Island City, in the county of 5 Queens, State of New York, have invented an Improved Vaporizer for Hydrocarbon-Engines, of which the following is a specification.

The main object of this invention is to provide a vaporizer for hydrocarbon-motors 10 which will allow the throttling of the explosive mixture and at the same time maintain the proper proportion of the air and gas, so that an engine may be run at high, intermediate, or low speed. This object I accomplish 15 by providing a plurality of liquid-hydrocarbon-feed inlets and air-inlets all leading to a common outlet to convey the vaporized mixture to the motor-cylinder and means for shutting off or opening as many of these combined hydrocarbon and air supplies as may be desired.

In the accompanying drawings, Figure 1 is a plan of my improved vaporizer and a hydrocarbon-feed device. Fig. 2 is a side elevation 25 thereof. Fig. 3 is a central longitudinal sectional view. Fig. 4 is a vertical section on line 4-4, Fig. 3. Fig. 5 is a development of the surface of my preferred form of valve. Fig. 6 is a sectional detail of the hydrocarbon-30 inlet. Fig. 7 is an inverted plan view of the plug, and Fig. 8 is a plan of a regulating-slide.

As shown in the drawings, R is a float-valve chamber of well-known construction adapted 35 to keep the level of the liquid hydrocarbon up to about the line $r-r$, as shown in Fig. 3. B is the body part of the vaporizer, having chambers C¹, C², C³, and C⁴ separated from each other by walls w. Each chamber has an 40 air-inlet opening O' O², &c. A nozzle t' t², &c., projects up into the mixing-chamber A' A², &c., from the hydrocarbon-feed pipe p.

The nozzles t', &c., are formed each with a cone-shaped mouth c' c², &c., having a cylindrical opening e' e², &c., immediately below, ending in a central threaded hole h' h², &c., of reduced diameter. Around this central threaded hole are small feed-openings

f' f², &c. A plug P' P², &c., having a cone-shaped upper part and a shank threaded at its 50 lower end, is adapted to fit in the nozzle t', &c., so as to prevent passage of hydrocarbon except through grooves g' g², &c., of properly-determined size in the wall of the cone-shaped plug P', &c.

55

Immediately above the plug I have shown each chamber A' A², &c., provided with an opening o' o², &c., with which can be made to register a port l' l², &c., in a throttle-valve V, rotating in its valve-casing C, secured to the 60 body part B. Between the body part B and valve-casing C, I prefer to place a removable perforated plate D, so that on using hydrocarbons of different qualities one such plate 65 may be withdrawn and be replaced by a plate having more or fewer openings, so as to regulate the supply according to the quality of the liquid hydrocarbon used.

An outlet-pipe S leads from the valve-casing C to convey the vaporized mixture to the 70 motor-cylinder. The valve V is a hollow cylinder provided with a shaft s, controlled by a lever or levers or any suitable means.

The cylinder has a large outlet-port L, open 75 in all operative positions to the outlet-pipe S to the motor. The valve V also has four other ports l' l² l³ l⁴, adapted on the rotation of the valve to open communication between more or fewer of the mixing-chambers C', &c., and the common outlet-pipe S. Port l' is 80 elongated to occupy a greater circumferential distance on the barrel than port l², while port l³ is less than l² and port l⁴ is still less in area, as seen in Fig. 5. It thus follows that by turning the valve port l' alone may be opened, 85 or ports l' and l² may be opened, or ports l' l² l³ may be opened, or all the ports may be opened to allow varying quantities of air and hydrocarbon to be vaporized and pass to the motor.

In operation, suppose the valve V to be in 90 the position shown, with the port l' alone open, liquid hydrocarbon occupying a position as shown by line $r-r$, which is determined by the float-valve in chamber R, level with the top of the grooves in the plugs without overflowing. At the port l' the suction acts to draw

95

the liquid upward, at the same time drawing air into the chamber A', where it mixes with and vaporizes the liquid, the vaporized mixture passing to the motor. If higher speed is wanted, the valve V is rotated to open the port t^2 also, so that the quantity of oil and of air drawn in and vaporized are proportionately increased. In like manner the feed of liquid and air increase proportionately upon the progressive movement of the valve to open more ports to the mixing-chambers, thus insuring the maintenance of proper proportion between the two elements of the mixture.

I claim as my invention—

- 15 1. A vaporizer for liquid hydrocarbons, comprising a plurality of liquid-hydrocarbon inlets, plurality of air-inlets, an outlet for the vaporized mixture, and a valve having a plurality of ports for simultaneously cutting off more or fewer of the hydrocarbon-inlets and air-inlets, substantially as described.
- 20 2. A vaporizer for liquid hydrocarbons, comprising a number of hydrocarbon-inlets, a separate air-inlet to each hydrocarbon-inlet, a common outlet-pipe and means for cutting off one or more of the pairs of hydrocarbon-inlets and air-inlets simultaneously, substantially as described.
- 25 3. A vaporizer for liquid hydrocarbons, comprising a number of inlets for hydrocarbon and means at all times to supply a constant flow to each inlet, an air-supply to each said inlet, an outlet for the vaporized mixture and a throttle-valve between the individual inlets and the outlet adapted to cut off or open more or fewer of the combined air and hydrocarbon inlets, substantially as described.

4. A vaporizer for liquid hydrocarbons, comprising an outlet-pipe, a throttle-valve opening thereto, a body part containing a plurality of 40 chambers, a separate passage from each chamber to the throttle-valve and an air-supply and a hydrocarbon-supply to each chamber, the throttle-valve being adapted to cut off more or fewer of the chambers from the outlet- 45 pipe, substantially as described.

5. A vaporizer for liquid hydrocarbons, comprising a body part containing a plurality of chambers, separated from each other, a nozzle with a plug in each chamber having grooves 50 of constant and predetermined size, means for feeding hydrocarbon to said grooves, air-inlets to the chambers, a valve having ports for registering with one or more chambers and a common outlet-pipe from the valve, substantially as described.

6. A vaporizer for liquid hydrocarbons, comprising a common outlet-pipe, a throttle-valve opening thereto, a body part containing a plurality of chambers, a separate passage from 60 each chamber to the throttle-valve, and an air-supply and a hydrocarbon-supply to each chamber, ports in the throttle-valve adapted to cut off more or fewer of the chambers from the outlet-pipe, and a removable perforated 65 plate between the chambers and valve, substantially as described.

In testimony whereof I have signed my name to this specification in the presence of two subscribing witnesses.

JOHN J. MACMULKIN.
